(57) CLAIM

The ornamental design for a toilet paper dispenser, as shown and described.

DESCRIPTION

FIG. 1 is a perspective view of a toilet paper dispenser showing the design;

FIG. 2 is a front elevational view of the toilet paper dispenser of FIG. 1;

FIG. 3 is a rear elevational view of the toilet paper dispenser of FIG. 1;

FIG. 4 is a top plan view of the toilet paper dispenser of FIG. 1;

FIG. 5 is a bottom plan view of the toilet paper dispenser of FIG. 1;

FIG. 6 is a left elevational view of the toilet paper dispenser of FIG. 1; and,

FIG. 7 is a right elevational view of the toilet paper dispenser of FIG. 1.

The dash-dash broken lines in the drawings depict portions of the toilet paper dispenser that form no part of the claimed design. The long dash-long dash broken lines in the drawings define the boundaries of the claim and form no part thereof.

1 Claim, 6 Drawing Sheets
